INVENTOR
BY Charles Krebs
Hedrick C. Fischer,
ATTORNEY

UNITED STATES PATENT OFFICE.

CHARLES KREBS, OF NEWARK, NEW JERSEY.

DEVICE FOR SEPARATING AND REPAIRING CHAINS.

Application filed January 19, 1922. Serial No. 530,353.

To all whom it may concern:

Be it known that I, CHARLES KREBS, a citizen of the United States, residing in Newark, in the county of Essex and State of New Jersey, have invented certain new and useful Improvements in Devices for Separating and Repairing Chains, of which the following is a specification.

One of the purposes of the present invention is to provide an implement for separating the links of a transmission belt chain in an easy and rapid manner by hand operated means, permitting its repair or adjustment as may be desired.

Another object is to produce a device that clasps or embraces the individual link to be operated upon in such manner as to firmly hold it, during the action of the link pin ejector, without deforming or defacing the tubular roller engaged or in any way affecting adjacent link elements.

A further aim is in the provision of a simple compact tool for the purpose mentioned, not readily liable to derangement.

With these objects in view the invention consists in the novel construction and arrangement of parts later described and claimed, and shown in the annexed drawing, constituting an essential part of this disclosure, and in which:—

Figure 1 is a perspective view of a chain link separator made in accord with the invention.

Figure 2 is a partial side, partial sectional view showing the construction of the same.

Figure 3 is a fragmentary top plan view illustrating its application.

Figure 4 is a plan view showing the type of chain on which the implement is adapted to operate, and indicating one of the links as separated by it.

The desirability of the tool about to be described will be clearly apparent to users of the type of transmission chains indicated, as due to wear original imperfections and like causes, it is often necessary to remove a link, which is by no means an easy matter without special devices.

By referring to the drawing the appliance will be seen to be comprised of a handle bar 10 suited for convenient manipulation and provided with an enlarged head 11 having a flat top surface 12 substantially level with the main portion of the handle bar.

A pair of blocks 14 and 15 are fitted to the

head 11, the block 14 being rigidly secured by a transverse pin 16 or other equivalent fastening means, a similar pin 17 fixed in the block 15, passing freely through a slot 18 in the head, the pin acting as a key and also limiting the movement of the block 15 which is slidable on the head.

The opposed faces of the blocks contain registering transverse through recesses 20 and 21, the material thereabove constituting jaws 22 and 23 cut away at the center to present equal semi-circular openings 24 and 25 and bevelled inwardly on each side as at 26 and 27.

The blocks together as a unit are drilled, as at 28, concentric with the jaw openings, and the head 11 is drilled in register therewith, the opening 29 being screw-threaded.

A handle 30 is formed with a rightangle bend 31 fitted to the threaded opening 29 and terminating in a projection 32, which obviously may be forcibly projected upward into the opening 28 or retracted by actuating the handle 30.

A rivet 33 or like fastening is fixed in the handle bar 10 and coiled about its body, below the head, is a wire 34 having opposed arms 35 extending over the head 11, these arms having angularly turned detent elements 36 projecting towards each other and adapted to hold the block 15 in contact with the fixed block, the ends 37 extending in parallel from the detents within a recess 15' of the movable block when the arms 35 are pressed inwardly, permitting the block to move away from its mate to allow insertion of the chain.

The chain, shown in detail in Figure 4, is composed of a plurality of tubular rolls 50, mounted on sleeves 51 rotatable on the bodies of pins 52 the sleeves 51 having ends which project through appropriate openings in the ends of inner link plates 53, connecting adjacent rolls in parallel pintles 52' formed on the ends of the pins passing through similar openings in like links 54, connecting the paired rolls to form a continuous chain the ends of the pintles being riveted in the last named, outer links.

In operation, the spring arms 35 are pressed towards each other to permit the detents 36 to enter the recess 15', the block 15 moved away from its mate, separating the jaws 22 and 23 to permit entering the chain, as shown in broken line in Figure 2; the jaws 110

are then closed to embrace the roll, the detents spring out to maintain them in operative, closed position, gripping the entered roll in a positive manner.

5 The handle 30 is then turned to advance the ejector 32, which coming in contact with the adjacent end of the pintle, forces the pin out of the links, bending the outer link plate outwardly, freeing the pin from the lower links and permitting the roll to be removed.

Although the foregoing is descriptive of the preferred embodiment of the invention, it will be apparent that minor changes may 15 be made in its construction, without the exercise of invention or conflicting with the scope of the claims hereto appended.

Having thus described my invention, what I claim as new and desire to secure by Letters Patent, is:—

20 1. A roller chain link separator comprising a handle, an enlarged cylindrical head at one end thereof, said head having a flat surface on one side adjacent the handle, a 25 block fixed rigidly on the outer end of said head, a second block slidable on the head, a keying means limiting the movement thereof, a forked resilient detent secured to said handle to extend over the mentioned flat surface and engage said sliding block when in 30 contact with said fixed block, said detent being receivable in a recess in the sliding block when retracted, gripping jaws formed on said blocks which together contain a circular opening, and a disrupter pin operable in 35

said head in axial alignment with the opening in said jaws.

2. A chain link separator comprising a handle, a jaw fixed at the end thereof, a mating jaw slidable on said handle, said jaws 40 being transversely recessed and axially bored to receive a chain section therebetween, a two pronged spring detent carried by said handle to hold said jaws when closed, a screw operable in said handle in register with the 45 bore of said jaws, a plunger on the end of said screw engageable with the joint pin of the chain, and a handle on said screw by which it may be operated.

3. A roller chain link separator comprising a handle, an enlarged cylindrical head at one end thereof, said head having a flat surface on one side adjacent the handle, a block fixed rigidly on the outer end of said head, a second block slidable on the head, a 50 pin fixed in said second block, said pin passing through a transverse slot in said head, overhanging jaws formed with the respective blocks adapted to embrace between them the half of a chain section including its roll, a 55 screw actuated plunger operable in said head in alignment with joint pin of the chain held in said jaws, and operating means for said plunger.

This specification signed and witnessed 65 this 18th day of January, 1922.

CHARLES KREBS.
